(57) **CLAIM**

The ornamental design for a rolling, strap-held, end holders for securing a folded canopy therebetween, as shown and described.

DESCRIPTION

FIG. 1 is a front elevation view of a rolling, strap-held, end rollers for securing a folded canopy therebetween showing my new design; the canopy is elevated from the storage roller for clarity of illustration;

FIG. 2 is a right side elevation view of FIG. 1;

FIG. 3 is a rear elevation view of FIG. 1;

FIG. 4 is a top plan view of FIG. 1;

FIG. 5 is a bottom plan view of FIG. 1;

FIG. 6 is a perspective view of FIG. 1;

FIG. 7 is a perspective view thereof showing the canopy in a storage condition;

FIG. 8 is a front elevation view of a second embodiment of the rolling, strap-held, end rollers for securing a folded canopy therebetween;

FIG. 9 is a right side elevation view of FIG. 8;

FIG. 10 is a rear elevation view of FIG. 8;

FIG. 11 is a top plan view of FIG. 8; and,

FIG. 12 is a bottom plan view of FIG. 8.
